(57) **CLAIM**

The ornamental design for a portable shop table, as shown and described.

DESCRIPTION

FIG. 1 is a perspective view of a portable shop table showing my design;

FIG. 2 is a front elevational view thereof;

FIG. 3 is an elevational view thereof from the right side;

FIG. 4 is a back elevational view thereof;

FIG. 5 is an elevational view thereof from the left side;

FIG. 6 is a top plan view thereof;

FIG. 7 is a bottom plan view thereof;

FIG. 8 is a bottom view thereof, as seen from line 8—8 in FIG. 2;

FIG. 9 is another bottom view thereof, as seen from line 9—9 in FIG. 2;

FIG. 10 is a perspective view of the bottom thereof; and, FIG. 11 is an enlarged, perspective view of the caster portion thereof encircled in FIG. 10.
